Philip S. McLean
ATTORNEY

This is a continuation-in-part of my application Serial No. 150,220, filed March 17th, 1950, now Patent No. 2,572,681 of October 23rd, 1951, in which ring forming fingers projecting from one side of a tubular rib are biased to enter and hold closed in slots provided in the opposite side of the rib.

Objects of the present invention, which is a continuation-in-part of the case identified, are to provide simple and practical mechanism for opening and holding open, the ring forming fingers for inserting or removing the leaves or filler.

Other special objects of the invention are to provide a ring opener of the character indicated which will open up the rings to the fullest extent required without straining or weakening the same and which will thereafter close or enable proper, full closing of the rings.

Other desirable objects attained by the invention are set forth or will appear in the course of the following specification.

The drawing accompanying and forming part of the specification illustrates a present practical embodiment of the invention. Structure, however, may be modified and changed as regards the immediate illustration, all within the true intent and broad scope of the invention as hereinafter defined and claimed.

Fig. 1 in the drawing is a broken and vertical cross sectional view of one of the present ring opening devices in the open position, and a mechanical binding of the normally closed ring type positioned therein, ready to have the rings sprung open;

Fig. 2 is a similar view showing the press closed and the rings sprung open and held in that relation for receiving a filler, indicated in broken lines;

Fig. 3 is a broken top plan view of the press with the binding dropped in position therein preliminary to shifting it to carry the rings into position under the ring opening presser feet;

Fig. 4 is a broken vertical sectional view on substantially the plane of line 4-4 of Fig. 1, showing the rings in the preliminary position inserted between the presser bars;

Fig. 5 is a similar view on substantially the plane of line 5-5 of Fig. 2, with the rings shifted and the bars pressing the same into the opened relation.

The mechanical binding shown is like that of the patent application above identified, comprising a tubular rib formation 7 having spaced

stiups 8 projecting from one side of the same and providing binder ring forming fingers stressed or biased in the contracting direction so that the ends of the same will normally enter and be retained in the slots 9 formed in the opposite side of the rib. This is the condition illustrated in Figs. 1, 3 and 4.

The mechanism for opening and holding the ring forming fingers in open relation is in the nature of a press having a lower, concave die member 10 for supporting the binding and an upper, companion die member having correspondingly curved, convex bars 11 entering within the rings and applying pressure to spread them open.

The latter result is accomplished by forming the companion die members on a curvature of greater radius than the radius of the normally closed binder rings. Thus the effect of these companion dies is to flatten out the portions of the rings gripped between the dies, substantially as shown in Fig. 2.

Fig. 2 also shows how with only those portions of the rings nearest the rib gripped between the dies, these root portions of the fingers will be temporarily flattened without disturbing the curvature of the end portions of the rings, so that as soon as pressure is released the resiliency of the material will cause the rings to constrict to their normal diameter, with the free ends of the rings entering the keeper slots 9 and being retained therein as before.

The presser bars 11, as shown in Fig. 3, are spaced in parallel relation sufficiently to permit entry of the binder rings therebetween and have notches 12 in the edges of the same to admit the continuous portions of the rings when the binding is shifted in the direction of the arrow to carry the root portions of the rings beneath the presser bars.

Fig. 4 shows how the binding may be entered in the press by dropping the rings straight down through the spaces 13 between the bars. This leaves the binding free to be shifted longitudinally to the left in Fig. 4, in the direction of the arrow, to carry the portions of the rings seated in the die concavity directly beneath the bars, as in Fig. 5.

Fig. 3 shows how the concave lower die may be slotted down at the one side, at 14, to admit the thinner portions 15 of the presser bars which are thus reduced in thickness to provide the notches 12.

The parallel bars 11 of the upper die member 55 are shown as having base portions 16 detachably

UNITED STATES PATENT OFFICE

2,608,700

BINDER RING OPENING DEVICE

Clarence D. Trussell, Turnwood, N. Y.

Application June 19, 1951, Serial No. 232,347

5 Claims. (Cl. 11—1)

1

The invention herein disclosed relates to mechanical bindings of the type covered in copending patent application Serial No. 150,220, filed March 17th, 1950, now Patent No. 2,572,681 of October 23rd, 1951, in which ring forming fingers projecting from one side of a tubular rib are biased to enter and hold closed in slots provided in the opposite side of the rib.

Objects of the present invention, which is a continuation-in-part of the case identified, are to provide simple and practical mechanism for opening and holding open, the ring forming fingers for inserting or removing the leaves or filler.

Other special objects of the invention are to provide a ring opener of the character indicated which will open up the rings to the fullest extent required without straining or weakening the same and which will thereafter close or enable proper, full closing of the rings.

Other desirable objects attained by the invention are set forth or will appear in the course of the following specification.

The drawing accompanying and forming part of the specification illustrates a present practical embodiment of the invention. Structure, however, may be modified and changed as regards the immediate illustration, all within the true intent and broad scope of the invention as hereinafter defined and claimed.

Fig. 1 in the drawing is a broken and vertical cross sectional view of one of the present ring opening devices in the open position, and a mechanical binding of the normally closed ring type positioned therein, ready to have the rings sprung open;

Fig. 2 is a similar view showing the press closed and the rings sprung open and held in that relation for receiving a filler, indicated in broken lines;

Fig. 3 is a broken top plan view of the press with the binding dropped in position therein preliminary to shifting it to carry the rings into position under the ring opening presser feet;

Fig. 4 is a broken vertical sectional view on substantially the plane of line 4-4 of Fig. 1, showing the rings in the preliminary position inserted between the presser bars;

Fig. 5 is a similar view on substantially the plane of line 5-5 of Fig. 2, with the rings shifted and the bars pressing the same into the opened relation.

The mechanical binding shown is like that of the patent application above identified, comprising a tubular rib formation 7 having spaced

secured by screws 17 on the upper end of a ram or slide 18 operating vertically in a guideway 19 in a bed or table structure 20. This ram may be operated by power or by a pedal, after the manner of a foot press.

The spaced bars of the upper die serve as guides to direct the binding into proper position supported on the lower, concave die, and then only a slight longitudinal movement is required to locate the rings in position beneath the presser elements of the upper die.

The rings are opened with a simple flattening out pressure which does not impart any permanent deformation. When pressure is released, therefore, the rings automatically close to the same, originally formed diameter.

The opening is accomplished without pulling or straining, so that it is not necessary to hold the tubular rib portion of the binding. It may be desirable to locate this rib in some approximate position near the ends of the presser bars, and for this purpose the bars are shown concavely recessed at the ends, at 21, against which the rib may be seated when the binding is first placed in the machine, as in Fig. 1.

If found desirable, the dies or either of them may be heated or cooled to avoid injury and to insure the rings returning to their fully closed condition.

The presser bars, instead of being supported at one side only in a comb-like structure such as shown, may be supported at both ends.

As a further alternative the presser bars 11 may be carried by a centrally disposed slide, with the slots 14 extending partly or full length across the lower concave die 10. This construction avoids a side ram or rams and provides a direct downward movement with a centered ram.

What is claimed is:

1. A machine for opening the normally closed rings of a binder having a tubular rib and elastic fingers forming rings projecting from the side of the same and comprising companion concave and convex die members of radius enough greater than the normal radius of the rings to relatively flatten portions of the rings engaged therebetween sufficiently to open them without permanently deforming them and said convex die member being composed of presser bars spaced to admit the rings of the binder therebetween and having clearances for the rings at one side to permit longitudinal shifting of the binder to carry the rings into position between the convex presser bars and the concave die member and means for relatively approaching said die members to effect the partial flattening and opening of the rings and for then separating the die members to permit the rings to close.

2. A machine for opening the normally closed rings of a binder having a tubular rib and elastic fingers forming rings projecting from the side of the same and comprising companion concave and convex die members of radius enough greater than the normal radius of the rings to relatively flatten portions of the rings engaged therebetween sufficiently to open them without permanently deforming them and said convex die member being composed of presser bars spaced to admit the rings of the binder therebetween and having clearances for the rings at one side to permit longitudinal shifting of the binder to carry

the rings into position between the convex presser bars and the concave die member, a bed supporting said concave die member and a slide operating in said bed toward and away from the concave die member and carrying the presser bars of the convex die member and means for effecting reciprocating movement of said slide to move the presser bars toward and away from the convex die member.

3. A machine for opening the rings of a binder having elastic rings tensioned in the fully closed relation and comprising companion concave and convex die members of radius enough greater than the normal radius of the rings to relatively flatten portions of the rings engaged therebetween sufficiently to open them without permanently deforming them, said convex die member being composed of presser bars spaced to admit the rings of the binder therebetween and having clearances to permit longitudinal shifting of the binder to carry the rings into position between the convex presser bars and the concave die member and a ram for operating said convex die member toward and away from the concave die member.

4. A machine for opening the normally closed rings of a binder having a tubular rib and elastic fingers forming rings projecting from the side of the same and comprising companion concave and convex die members of radius enough greater than the normal radius of the rings to relatively flatten portions of the rings engaged therebetween sufficiently to open them without permanently deforming them and said convex die member being composed of presser bars spaced to admit the rings of the binder therebetween and having clearances for the rings to permit longitudinal shifting of the binder to carry the rings into position between the convex presser bars and the concave die member and a stop shoulder at one end of the presser bars for engagement by the tubular rib of the binder to locate the binder with portions of the rings adjoining the tubular rib in position for relative flattening engagement between the presser bars and concave die member and means for relatively approaching and separating the die members to effect opening and closing movements of the rings.

5. A machine for opening the rings of a binder having elastic rings tensioned in the fully closed relation and comprising companion concave and convex die members of radius enough greater than the normal radius of the rings in the closed relation to partly flatten portions of the rings engaged therebetween sufficiently to open the rings without deforming the same, means connecting said convex presser bars together in position to engage inside the binder rings and means for effecting movement of said convex presser bars toward and away from said concave die member.
